JEFFERSON KINDLEBERGER AND WILLIAM AUGUSTUS ARNOLD, OF SAN FRANCISCO, CALIFORNIA, ASSIGNEES TO "THE INVENTORS' ASSOCIATION, OF SAN FRANCISCO, CALIFORNIA."

Letters Patent No. 95,355, dated September 28, 1869.

IMPROVEMENT IN MACHINE FOR WIRING BLINDS.

The Schedule referred to in these Letters Patent and making part of the same.

To all whom it may concern:

Be it known that we, JEFFERSON KINDLEBERGER, and WILLIAM AUGUSTUS ARNOLD, of the city and county of San Francisco, State of California, have invented an Improved Double-Acting Wiring-Machine for Blinds; and we do hereby declare the following description and accompanying drawings are sufficient to enable any person skilled in the art or science to which it most nearly appertains, to make and use our said invention or improvements, without further invention or experiment.

The object of our invention is to provide an improved machine for wiring together, at one operation, the rods and shades of window-blinds or screens; and

It consists of a table, along which the rod is moved by a pawl, regulated to feed it the proper distance for the particular blind in process of manufacture.

The wires for the rods are placed upon a curved holder, having a space beneath it just the thickness of one wire, and an arm operated by a lever, presses the wire forward into the rod. The rod is then moved along the proper distance, where the wire just fastened to it will stand over the edge of a shade, which has been placed in the proper position.

Another wire-holder or conductor similar to the first, is placed here, and the wires from this are pressed downward by an arm connected with the main or hand-lever, so that one leg of the staple formed by the bent wire will pass through the wire loop which is fastened to the rod, as this last wire is forced into the shade, when the work is completed.

To more fully illustrate my invention, reference is made to the accompanying drawings, forming a part of this specification, in which—

Figure 1 is a side view of the machine, showing the lever.

Figure 2 is a top view.

Figure 3 is a back view.

Figure 4 is a front view, taken from the side marked x, fig. 1.

A is a table or plate, to which the rest of the frame A' is attached, so as to support the different portions of the mechanism.

To this frame A' the lever B is pivoted at B', and operates the bar D for forcing the wires into the shades, and also by intervening levers the bar N, which forces the wires into the rods.

The lever B is extended down beyond its point of support at B', and has the pawl E pivoted to it, so that when the lever is forced down this pawl is drawn back, but when it is raised, the pawl forces the rod along by means of notches in the side of the rod, into which the pawl falls. These notches are made at such a distance apart as to suit the style of blind to be made.

The rod is kept in position and steadied, by an elastic arm, F, which is attached to the side of the frame A'.

O is the support and conductor of the wires for the rods. These wires being already bent, the conductor is filled with them, and they are kept in place by the guard R.

The conductor O is attached to an adjustable plate, S, so that there will be a space sufficiently large to admit one of the wires to pass beneath the conductor.

The wire is moved forward by a sliding bar, N, which operates in a groove in the plate S, and presses the wire into the rod, after which it is retreated beyond the lower end of the conductor O, and another wire drops down before it, to be forced forward in a like manner.

The arm N is operated by a lever, M, which has its fulcrum at a point on the frame A', and is in turn moved by a sliding bar, L, at the top of the frame.

This bar has a bevelled or angular projection, a, rising from its upper side close to the lever B, so that as the lever is pressed down, it forces the bar L to move along, and thus operates the lever M.

The plate S has two slots, and by loosening the bolts T, which pass through these slots, and turning the screws V, the plate may be moved to or from the point where the shade is placed, so as to increase or diminish the space between the shades.

The block G, against which the rod rests when a wire is pressed into it, is also adjustable to the different sizes of the rods which may be used.

That part of the mechanism for wiring the rods to the shades consists of a conductor, O, similar to O, but so placed that the wires stand vertically when they leave it at its lower end and are forced down by the bar D, which is operated directly from the lever B, either by direct connection, as shown, or by the intervention of a connecting-rod.

The shades are placed one at a time on their edges, upon the adjustable screws H, and their ends rest against the guide I. The rod is passed along by the pawl or feeder E, during the upward motion of the lever B. The motion also raises the arm D, and releases the bar L, which is forced back by the spring K, and thus through the lever M, retracts the bar N.

When the lever B is pressed down, the bar N forces one wire from the conductor O into the rod, and the arm D forces one from the conductor O into the shade, one of the sides of the wire passing through a wire loop, which was formed on the rod by the previous motion, and which has now been carried to the proper position by the pawl E.

The conductor O is made so as to form an arc of a circle, the wires being placed on the convex or upper side, this being the only form which will feed the wires

regularly and singly. Any other form, where it is necessary to introduce the wires from the side, must clog the passage.

The conductor C, which must deliver its wires so that they stand vertically, is also made the arc of a circle, but the wires are in this case placed on the concave side, which is uppermost.

In either of these cases, if a straight conductor is used, the wires will crowd over each other and feed more than one at a time, so as to render the machine impracticable.

Having thus described our invention, What we claim as new, and desire to secure by Letters Patent, is—

1. The above-described rod-wiring device, consisting of the conductor O, with the guard R, and the

sliding bar N, lever M, and sliding bar L, operated by the lever B, substantially as described.

2. In combination with the above-claimed device, the pawl E, pivoted upon the bent lever B, for feeding forward the rods, substantially as described.

3. The combination, with the rod-wiring device above claimed, of the device for wiring the blind-slats to the rods, substantially as herein set forth.

In witness whereof, we have hereunto affixed our hands and seals.

JEFFERSON KINDLEBERGER. [L. S.]
WILLIAM AUGUSTUS ARNOLD. [L. S.]
